SPRING STRUCTURE FOR MATTRESSES
AND THE LIKEAlex H. Olson, Evanston, Ill., assignor to Joseph
W. Droll, Chicago, Ill.

Application November 29, 1933, Serial No. 700,189

4 Claims. (Cl. 5—247)

The invention relates to improvements in spring structures for mattresses and the like.

One object of the invention is to improve spring structures of the type in which the springs are provided with divergent arms between the top and bottom frames of the mattress, by forming on the springs cross-members to serve as connections between the frame members and to support the padding over the structure.

Another object of the invention is to provide an improved spring structure which comprises frame-members formed of wire coils and wire springs having central coils and divergent arms between the coils and the top and bottom frames of the mattress, with integral side-extensions through adjacent frame members which are locked or connected together so that the spring action of the coils will be supplemented by the torsional resistance of the side members to the movement of the arms.

Other objects of the invention and the advantages and characteristics of the present spring structure will appear from a consideration of the following detailed description.

The invention consists in the several novel features which are hereinafter set forth and are more particularly defined by claims at the conclusion hereof.

In the drawings, Figure 1 is a partial plan of a spring structure embodying the invention. Fig. 2 is a similar view on a larger scale, parts of the longitudinal frame members being shown in section. Fig. 3 is an enlarged section taken on line 3—3 of Fig. 1 and showing the spring portions of the structure slightly compressed. Fig. 4 is a detailed perspective of one of the springs and illustrating a mating spring in dotted lines. Fig. 5 is a perspective of a pair of mated springs. Fig. 6 is a perspective of a pair of mated springs embodying a modified form of the invention. Fig. 7 is a horizontal section through the springs shown in Fig. 6 connected to a pair of helicals.

The invention is exemplified in a spring structure comprising a top and a bottom frame, and a series of springs A between the top and bottom frames of the construction hereinafter described. Each frame consists of a series of equidistantly spaced, longitudinally extending wire coils 10 and a pair of end wire coil members 11. The outer longitudinal members 10 are suitably secured to the end members 11 to form a rectangular margin and the intermediate longitudinal members 10 have their ends secured or hooked to the end-members 11 as shown in Figs. 1 and 2.

The springs A are arranged in rows between the two frames, there being one row between each pair of longitudinal members and between the upper and lower frames. Each row extends from one end of the structure to the other. Each of the springs A is formed of a single strip of spring wire bent to form, a central coil 12, the axis of which is substantially horizontal; upwardly and downwardly extending divergent spring-arms 13 and 14; side members 15 on the upper and lower ends of arms 13, 14 respectively, which form members to extend through the longitudinal coil members 10 of the upper and lower frames respectively; cross-members 17 which extend substantially at right angles from the upper and lower side-members 15 respectively, are parallel with each other, and extend across and form a tie or connection and support between adjacent longitudinal members 10; and side members 19 which extend approximately at right angles from the cross-members 17 respectively, and are parallel to the side members 15 and arranged so that they extend through the wire coil members that are adjacent to the members through which the side-members 15 extend. Each cross member 17 is formed with an offset loop 21 to support the padding of the mattress between the cross-members 17 of the springs A, and also to render the cross-members flexible.

The springs A are mated together in pairs so that the divergent arms of one spring of each mated pair will extend between vertically aligned members 10 and the divergent arms of the other spring of the mated pair will extend vertically between the next adjacent upper and lower members 10. This arrangement results in having the side members of the mated springs overlap in the wire coil members 10 and in having the cross members extend between the members 10. It also results in causing the springs of a mated pair to coact in receiving the imposed load. The end of each side-member 19, of each spring A is provided with a hook 22 which is adapted to hook around and overlap a cross member 17 of the mating spring, so as to stiffen the action of the cross-members. The cross-members 17 of each spring serve flexibly to connect or tie the longitudinal members 10 together transversely of the structure and also serve to support the mattress padding 23 which is usually placed above and below the spring structure inside of the mattress cover.

An important result of providing cross members 17, on the springs is that each spring is connected to the horizontally adjacent frame mem-

bers 10 so that the side members 15 will connect said frame-members to distribute the load and resist the rotation of side-members 15 in the wire-coil members, and to stiffen or supplement 5 the spring action of the coils 12 and the divergent arms 13, 14.

In assembling the structure, the frame-coils are rotated successively around the contiguous side members 15 and 19 of the springs of a longitudinal row. The end members 11 between the longitudinal coil members 10 are coiled around the offset loops 21 of the end row of springs. The mated springs A of one row are laterally offset and placed intermediate the mated springs of 15 contiguous rows as shown in Fig. 1 so that the springs will be distributed throughout the structure to avoid continuous portions which are not 20 spring supported. The usual tufts (not shown) will be sewed to the mattress through the spaces between the springs as well understood in the art.

In the form of the invention illustrated in Figs. 6 and 7, each spring, in lieu of being provided with a coil 12, is provided at its central portion with a pair of oppositely extending longitudinal loops 24^a, 24^b. These loops permit flexing of the divergent arms 13' and 14' which extend from the loops to the side members 15' and also measurably resist longitudinal deflection of 30 the central portions of the arms. In this construction the loops do not interfere with the free insertion of the tufting ties.

In use, when a load is placed in the region over one of the mated pair of springs, there will be 35 deflection of the adjacent longitudinal members 10 produced by the cross-members. The spring action of coils 12 or loops 24^a, 24^b and divergent arms 13 and 14 or 13' and 14' will be supplemented by the torsional resistance of the side 40 members of the springs. The compression of the mattress at the frame-members and the side members 15, will, through the cross-members 17 exert a cross and vertical deflection of the longitudinally adjacent side members 19. In this 45 manner localized pressure or load is distributed over a wide area of the spring structure and this makes it possible to avoid the use of stiff or heavy springs in the manufacture of mattresses. The spring structure yields easily to support, with 50 comfort, the body on the mattress. All portions of the structure are flexible and evenly spring supported.

The invention exemplifies a spring structure for a mattress and the like in which individual 55 springs of the cantilever type are interposed between the top and bottom frame members so that the deflecting stresses will be effectively distributed over a wide area to produce a comfortable mattress or rest. The construction exhibited 60 makes it possible to provide a spring structure for a mattress which is light in weight.

The invention is not to be understood as restricted to the particular details set forth, since 65 these may be modified within the scope of the appended claims, without departing from the spirit and scope of the invention. While the invention has been described for use in a mattress, it will be understood that it is applicable to springs for supporting mattresses.

70 Having thus described the invention, what I claim as new and desire to secure by Letters Patent, is:

1. In a spring structure of the character described, the combination of an upper and a lower frame, one of which comprises a horizontal series

of parallel, equidistantly spaced, wire coil members, and rows of mated pairs of wire springs extending between the two frames and longitudinally of the wire coil members of the one frame, one of the springs of each mated pair comprising a spring element disposed substantially centrally between the two frames, a pair of straight, divergent arms extending one upwardly and the other downwardly from said spring element, means connected to the outer end of one of the arms for connecting the same to the other frame, a horizontally extending, first side member connected at one end thereof to the outer end of the other divergent arm and extending through a portion of one of the wire coil members of said one frame, a horizontal cross member connected at one end to the other end of said first side member and extending between said one wire coil member and one of the adjacent wire coil members of said one frame, and a horizontally extending, second side member connected at one end thereof to the other end of the cross member so that it extends from the cross member in the same direction as said first side member, and extending through a portion 10 of said one adjacent wire coil member and having a hook at its other end, the other spring of each mating pair being the same in construction as the one spring but arranged in opposite relation and so that the first and second side members 15 thereof lap respectively the second and first side members of said one spring and extend through the same portions of the wire coil members and so that the end of the cross member thereof that is connected to the first side member is hooked 20 by the hook on the second member of the one spring and its hook at the end of its second side member is hooked around the end of the cross member of said one spring that is connected to the said other end of the first side member of 25 said one spring.

2. In a spring structure of the character described, the combination of an upper and a lower frame, one of which comprises a horizontal series 30 of parallel, equidistantly spaced, wire coil members, and rows of mated pairs of wire springs extending between the two frames and longitudinally of the wire coil members of the one frame, one of the springs of each mated pair comprising a spring element disposed substantially centrally 35 between the two frames, a pair of straight, divergent arms extending one upwardly and the other downwardly from said spring element, means connected to the outer end of one of the arms for connecting the same to the other frame, a horizontally extending, first side member connected at one end thereof to the outer end of the other divergent arm and extending through a portion 40 of one of the coil members of said one frame, a horizontal cross member connected at one end to the other end of said first side member, and extending between said one wire coil member and one of the adjacent wire coil members of said one frame and having a U-shaped 45 offset in the central portion thereof extending away from said first side member, and a horizontally extending, second side member connected at one end thereof to the other end of the cross member so that it extends from the cross member in the same direction as said first side member, and extending through a portion of said one adjacent wire coil member, the other spring of each 50 mating pair being the same in construction as the one spring but arranged in opposed relation and so that the first and second side members thereof 55

lap respectively the second and first side members of said one spring and extend through the same portions of the wire coil members and so that the U-shaped offset of the cross member 5 thereof projects in the opposite direction from the offset of the cross member of the one spring.

3. In a spring structure of the character described, the combination of an upper frame comprising a horizontal series of parallel, equidistantly spaced, wire coil members, a lower frame 10 also comprising a horizontal series of parallel, equidistantly spaced, wire coil members and arranged so that the members thereof are vertically aligned with wire coil members of the upper frame, and rows of mated pairs of wire springs 15 extending between the two frames and longitudinally of the wire coil members, one of the springs of each mated pair comprising a spring element disposed substantially centrally between the two frames, a pair of straight, divergent arms 20 extending one upwardly and the other downwardly from said spring element, a pair of parallel, horizontally extending, laterally spaced side members with a cross member therebetween, carried by the one arm and arranged so that the side members extend through portions of two adjacent wire coil members of the upper frame and the cross member extends between said portions, and a second pair of parallel, laterally spaced, side 25 members with a cross member therebetween, carried by the other arm and arranged so that the side members extend through portions of the two wire coil members of the lower frame that are directly beneath said two wire coil members of the upper frame and so that the cross member 30 extends between such two wire coil members of the lower frame, the other spring of each mated pair being the same in construction as the one spring but arranged in opposite relation and so that the side members carried by the upper arm 35 lap the upper side members of the one spring and extend through the same portions of the two wire coil members in the upper frame and the side members carried by the lower or downwardly extending arm lap the lower side members of the one spring and extend through the same portions of the two wire coil springs of the lower frame. 40

45

4. In a spring structure of the character described, the combination of an upper frame comprising a horizontal series of parallel, equidistantly spaced, wire coil members, a lower frame also comprising a horizontal series of parallel, equidistantly spaced, wire coil members and arranged so that the members thereof are vertically aligned with wire coil members of the upper frame, rows of mated pairs of wire springs 5 extending between the two frames and longitudinally of the wire coil members, one of the springs of each mated pair comprising a spring element disposed substantially centrally between the two frames, a pair of straight, divergent arms extending one upwardly and the other downwardly from said spring element, a pair of parallel, horizontally extending, laterally spaced side members with a cross member therebetween, carried by the one arm and arranged so that the side members extend through portions of two adjacent wire coil members of the upper frame and the cross member extends between said portions, and a second pair of parallel, laterally spaced, side members with a cross member therebetween, carried by the other arm and arranged so that the side members extend through portions of the two wire coil members of the lower frame that are directly beneath said two wire coil members of the upper frame and so that the cross member extends between such two wire coil 20 members of the lower frame, the other spring of each mated pair being the same in construction as the one spring but arranged in opposite relation and so that the side members carried by the upper arm lap the upper side members of the one 25 spring and extend through the same portions of the two wire coil members in the upper frame and the side members carried by the lower or downwardly extending arm lap the lower side members of the one spring and extend through the same portions of the two wire coil springs of the lower frame, and hooks on the free ends of certain of the upper and lower side members of each pair of mated springs extending around the adjacent cross members and serving to hold the 30 springs in connected relation. 35

ALEX H. OLSON.
